DESIGN FOR A COMBINATION VANITY AND CIGARETTE CASE

Theodore Adams, Providence, R. I.

Application July 26, 1940, Serial No. 93,945

Term of patent 7 years

To all whom it may concern:

Be it known that I, Theodore Adams, a citizen of the United States, residing at Providence, in the county of Providence and State of Rhode Island, have invented a new, original, and ornamental Design for a Combination Vanity and Cigarette Case, of which the following is a specification, reference being had to the accompanying drawing, constituting a part thereof.

Fig. 1 is a perspective view in closed position of a combination vanity and cigarette case showing my new design;

Fig. 2 is a side elevational view thereof; and
Fig. 3 is a perspective view in open position.

I claim:

The ornamental design for a combination vanity and cigarette case, substantially as shown.

THEODORE ADAMS.
